UNITED STATES PATENT OFFICE.

GEORGE J. MURDOCK, OF BROOKLYN, NEW YORK.

FILE AND HOLDER.

SPECIFICATION forming part of Letters Patent No. 309,153, dated December 9, 1884.

Application filed July 16, 1884. (No model.)

To all whom it may concern:

Be it known that I, GEORGE J. MURDOCK, a citizen of the United States, and a resident of Brooklyn, in the county of Kings and State 5 of New York, have invented certain new and useful Improvements in Files and Holders; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a side view of my improved file 15 and holder. Fig. 2 is a similar view of the holder. Fig. 3 is a view of the under side of the same. Fig. 4 is a cross-section on line x x , Fig. 3. Fig. 5 is a view of the file. Fig. 6 is a cross-section on the line x x , Fig. 5; and 20 Fig. 7 is a view of the thumb-nut and screw.

Similar letters of reference indicate corresponding parts in all the figures.

My invention has relation to holders for files; and it consists in the improved construction and combination of parts of the 25 same, as hereinafter more fully described and claimed.

In the accompanying drawings, the letter A indicates the holder, which may be secured 30 in a handle, B, and may have upon one edge a graduated rule, C, and the outer end of this holder, which is a straight flat bar, is provided with a lug or short rib, D, having beveled sides and projecting from the under side of 35 the holder, while the inner end of the holder has a longitudinal slot, E.

F is the file-blade, which has two slots or notches, G and H, one at each end, the sides of which slots are beveled to both sides, adapting the one to fit upon the beveled rib at the 40 end of the holder and the other to be held by the beveled head I of a screw, J, which passes through and slides in the slot in the inner end of the holder, and is provided with a thumb-nut, K. It will be seen that, the side edges of 45

the slots being beveled to both sides of the file-blade, the said blade may be turned so as to expose either side; and it will be seen that the blade may be secured in the holder by slipping the notch at one end upon the beveled rib at the end of the holder, whereupon the head of the screw may be slipped into the other slot, sliding in the slot in the holder, and be secured by means of the thumb-nut. 50

Having thus described my invention, I claim 55 and desire to secure by Letters Patent of the United States—

1. The combination of a holder provided with a lug at its outer end, the said lug increasing in diameter toward its outer end, a 60 file-blade having a notch or slot at its end corresponding in shape to the lug and fitting upon the same, and means, substantially as described, for securing the inner end of the file, as and for the purpose shown and set forth. 65

2. The combination of a holder provided at its outer end with a lug increasing in diameter toward its outer end, and having a longitudinal slot at its inner end, a file-blade having slots or notches at its ends increasing in 70 diameter toward both sides, and a screw having a head increasing in diameter toward its outer end, and provided with a thumb-nut, as and for the purpose shown and set forth.

3. The combination of a holder having a 75 graduated rule at one edge, and having a lug or short rib at its outer end, having beveled sides and a longitudinal slot at its inner end, a file-blade having a slot or notch at each end, having the side edges beveled toward both 80 sides, and a screw having a beveled head and provided with a thumb-nut, as and for the purpose shown and set forth.

In testimony that I claim the foregoing as my own I have hereunto affixed my signature 85 in presence of two witnesses.

GEORGE J. MURDOCK.
